UNITED STATES PATENT OFFICE.

HENRY J. FREY, OF PITTSBURG, PENNSYLVANIA.

WINDOW-CHAIR.

No. 901,801.

Specification of Letters Patent. Patented Oct. 20, 1908.

Application filed November 27, 1907. Serial No. 404,117.

To all whom it may concern:

Be it known that I, HENRY J. FREY, a citizen of the United States of America, residing at North Side, Pittsburg, in the county 5 of Allegheny and State of Pennsylvania, have invented certain new and useful Improvements in Window-Chairs, of which the following is a specification, reference being had therein to the accompanying drawing.

10 This invention relates to window chairs, particularly designed for janitors for cleaning the windows of buildings.

The primary object of my invention is to provide a chair that can be easily and quickly fastened to the sill of a window, to insure perfect safety of a person upon the outer side of a building when cleaning windows.

Another object of this invention is to 20 provide a portable window chair or scaffold that can be used by janitors, painters and such artisans when cleaning or decorating the exterior of a building. In this connection, the invention is also designed for 25 residences and can be conveniently used for the purpose above specified. In construction the seat is extremely simple, durable, and highly efficient for the purpose for which it is intended.

30 With the above and other objects in view, the invention consists in the novel construction, combination and arrangement of parts to be hereinafter described, and then specifically pointed out in the appended claims.

35 In the drawings: Figure 1 is an elevation of a window chair as secured to a window sill, Fig. 2 is a longitudinal sectional view of the same, Fig. 3 is a bottom plan view of the chair, and Fig. 4 is a cross sectional view 40 of a portion of the chair.

To put my invention into practice, I construct a chair which can be readily used as such or as a window-chair, platform or scaffold. The seat comprises a seat 1 having side arms 2, front legs 3, and a back 4 terminating in rear legs 5. The bottom of the seat 1 is provided with longitudinally disposed cleats 6, these cleats being arranged in two sets to serve functionally 50 as guides for plates 7.

The front legs 3 are connected by a brace 8 cut away as at 9 to permit of the ends of the plates 7 protruding in front of the seat, as will be presently described.

55 The plates 7 are provided with blocks 10 supporting transverse bars 11 and depend-

ing clamping members 12, these clamping members being arranged at an angle to the plate 7, whereby when the seat is placed upon a window-sill, said clamping members 60 besides engaging the outer side of the building will support the projecting part of the seat. This is clearly shown in Fig. 1 of the drawings, where 13 designates the windowsill of a building 14. The clamping members 12 are further braced by longitudinally disposed bars 15 and angle plates 16, these plates being secured to the outer sides of the clamping members 12 and the bars 15.

The transverse bars 11 carry interiorly 70 threaded bearings 17 for a longitudinal screw 18, said screw having its forward end revolubly held in the brace 8 by collars 19. This end of the screw terminates in a rectangular shank 20, whereby a crank handle, 75 wrench or similar instrument (not shown) can be placed upon the screw 18 to move the clamping members 12 into and out of engagement with the building. The rear end of the screw is threaded in the bearings 22 80 carried by the rear edge of the board 1.

To protect the window-sill 13 from being marred by the chair, I arrange a felt 21 or similar material under the board 1 and in the rear of the front legs 3.

85 It is thought that the manner of clamping the chair to a window-sill will be fully understood, besides the fact that the seat can be used as an ordinary chair when not employed for the main purpose above specified.

It is obvious that such changes in the size, proportion and minor details of the invention as are permissible by the appended claims can be resorted to without departing 95 from the scope of the invention.

Having now described my invention what I claim as new, is:—

A window chair comprising a seat, two sets of cleats secured to the lower face thereof, 100 each set arranged at one side of the center of the seat, a slideable plate positioned between the cleats of each set, a pair of blocks suitably spaced apart and depending from the lower face of each of said plates, said 105 blocks of less width than the width of the plates, an angularly disposed clamping member depending from each set of plates and abutting against the blocks carried by its respective plate, a pair of bars arranged 110 below a cleat of each set of cleats and having their ends abutting against the clamping

members and fixedly secured to the blocks, a brace secured to the front of the seat and depending from the lower face thereof, said brace cut away to permit of the passage of 5 said plates, a screw bearing secured to the rear of the seat depending from the lower face thereof, screw bearings carried by the bars, a rotatable screw extending through said brace engaging in the screw bearing 10 secured to the seat and engaging the screw

bearings carried by the bars, said screw in connection with said bearings adapted when rotated to shift the plates whereby the clamping members are adjusted.

In testimony whereof I affix my signature 15 in the presence of two witnesses.

HENRY J. FREY.
